AIR CONDENSER

Application filed January 31, 1927. Serial No. 164,695.

This invention relates to electrical condensers, and more particularly to variable air condensers; and has special reference to the provision of an improved variable air condenser of the multi-unit type designed for use in tuned radio receiving circuits for producing a uni-control or simultaneous adjustment of successive or cascaded circuits.

For simultaneously adjusting the constants of cascaded radio frequency circuits for tuning the same in unison and to the frequency of the received wave, it is the practice in the art to mechanically couple the tuning control devices, such for example as the tuning condensers or inductances in the circuits so that these may be adjusted by the manipulation of a single control element. Where condensers are employed as the tuning devices, the desired results are generally accomplished either by mechanically coupling the rotor shafts of separate condensers or by building the condenser units in a single assembly with the rotors of the units mounted on a single shaft. In either form of construction it is an important desideratum to balance and equalize the tuning devices with great precision and accuracy throughout the whole tuning range, so that the oscillation constants of the cascaded circuits may be adjusted to the same value with optimum precision throughout the whole wave length range through which the system is tunable.

To equalize the tuning operations, the condensers must be carefully matched or balanced so that the calibration curves of the same, especially when the condensers are in connected circuit arrangement, are substantially identical. Considerable difficulty has been experienced in the art in producing an exact match or equalization of the condenser units to meet service requirements, particularly in high precision sets, in spite of the fact that the condensers are capable of being standardized and built with sufficient precision by present manufacturing methods. It has been found, for example, that even though the condenser units which are coupled together for simultaneous adjustment or uni-control, are adjusted and assembled by the manufacturer so that a balance is obtained,

the desired balance or equalization will be disturbed when the condensers are arranged in circuit in the building of a receiving set and the balance of the condenser units themselves will not be maintained in service due generally to some structural instability of the condenser assembly. The disturbance of equalization when the condensers are connected in circuit is due to inequalities of the circuit wirings and to reactions between parts of the apparatus of the receiving set and the instability found in service is due to inherent mechanical forces and stresses active on the condenser parts to alter or distort the same and vary the capacities of the respective condenser units, especially when such condenser units are built or stacked up in a single assembly.

The prime desideratum of my present invention comprehends the provision of improvements in the manufacture of multiple variable condensers whereby the condenser units of the multiple assembly may be matched or equalized prior to as well as after being arranged in circuit in a cascaded tuned receiver, with the forces and stresses of the condenser assembly mechanically balanced and counteracted so that any structural instability of the built-up assembly which may give rise to distortion in use or service is effectively inhibited, with the result that the condenser units when once matched or balanced by the manufacturer of receiving sets, will be maintained in balanced relation in normal use even for an extended period of time.

To the accomplishment of the foregoing and such other objects as will hereinafter appear, my invention consists in the elements and their relation one to the other, as hereinafter more particularly described and sought to be defined in the claims; reference being had to the accompanying drawings which show the preferred embodiments of my invention, and in which:

Fig. 1 is a plan view of the multiple condenser embodying the principles of my invention with parts broken away and other parts shown in section,

Fig. 2 is a side elevational view thereof with parts broken away, and

Fig. 3 is a cross-sectional view thereof taken in the plane of the line 3—3, Fig. 2.

5 Referring now more in detail to the drawings, I show a multiple variable air condenser comprising a frame structure generally designated as F and a plurality of condenser units generally designated as C¹, C² and C³ mounted in built-up or stacked relation on the frame structure F, each of the condenser units including a stator and a rotor plate set designated respectively by s and r with an exponent corresponding to the condenser unit of which it forms a part.

The frame structure F comprises a metal enclosure or housing having the front and rear end walls 10 and 11, the side walls 12 and 13, and the bottom wall 14, all preferably 20 integral and desirably made as a casting so as to provide a rigid supporting structure for the condenser units. Said frame housing or casing is so designed that its enclosing walls form a static shield for the condenser units, 25 the depth of the frame casing being such as to shieldingly enclose the condenser plate sets in all positions of the rotors of such plate sets, as will be clearly seen from a consideration of Figs. 2 and 3 of the drawings. The bottom wall of the frame casing F may preferably be provided with the integral threaded lugs 15, 15 forming supporting legs for the frame, the said lugs being adapted to receive securing elements for 30 anchoring the condenser assembly to a suitable support. Desirably parts of the casing frame are cut away to permit ready assembly of the parts and to give access to other parts, the bottom wall 14 being provided with 35 the windows or openings 16, 16 and the front end wall 10 being provided with the open-ended slot 17, while the side walls are provided with such cut-aways as at 18, 18.

Each of the rotor plate sets r', r², r³ comprises a plurality of condenser plates 19, 19 affixed to a sleeve 20, each sleeve being axially adjustable on a shaft 21, and fixed in adjusted position by means of set screws 22, 22. The shaft 21 forms a common shaft for all of 40 the rotor plate sets and is journalled in the front and rear walls 10 and 11 of the casing frame F by means of conical bearing sleeves 23 and 24 which may be adjustably fixed to the shaft 21, which bearing sleeves cooperate 45 with mating bearing elements 25 and 26 respectively, the latter being threadedly adjustable in the journalling parts 10' and 11' of the front and rear frame walls, adjusting nuts 27 and 28 being provided for fixing the 50 threaded bearing elements 25 and 26 in adjusted position. The shaft 21 is provided with an extension 21' for receiving a control element such as a dial. With this construction 55 it will be seen that the rotor assembly comprising all the rotor plate sets may be ad-

justed axially in the frame F and fixed in adjusted position, and that the independent rotor plate sets r', r² and r³ may be independently adjusted axially of the common rotor shaft.

70 The stator plate sets s', s² and s³ each comprises a plurality of condenser plates 29, 29 arranged to be interleaved with the rotor plates 19, 19 the stator plates of each of the stator sets being carried at their opposite sides by posts or blocks 30 and 31 which are insulatably mounted from each other and from the frame F.

75 For insulatably mounting the stator plate sets on the frame, there are provided at each end of the condenser assembly a plurality of insulating members, a pair of insulating members 32 and 33 being provided for the longitudinal series of posts 31 and a second pair of insulating members 33' and 34 being 80 provided for the other longitudinal series of posts 30, 30. For insulatably mounting the stator plate sets from each other, I provide additional insulating members interposed between the stator posts, a pair 35 and 36 of 85 such members being provided for the post series 31 and another pair 37 and 38 of such insulating members being provided for the series of posts 30. The posts and insulating members are interlocked without employing any securing screws or devices by providing stud portions 39 (see Fig. 1) at the opposite ends of the posts, which portions are received by the central bores of the insulating members, cup-shaped elements 40 being also preferably provided for seating the opposite ends of each of the insulating members. With 90 this construction it will be seen that the stator plate sets of the stator assembly are mutually supported one on the other by interposed insulating members along at least two lines of support arranged on opposite sides of the rotor shaft.

95 I have found it highly desirable for the purpose of securing a matching of all the 100 condenser units throughout the whole tuning range to so support the stators as to permit independent adjustment of one side of the stator assembly with respect to the other side thereof; and in the preferred construction I 105 provide means for so mounting the stator assembly as to permit adjustment of both sides of the same axially along the lines of support thereof. To accomplish this purpose I 110 provide a plurality of adjustable supporting elements 41, 42, 43 and 44 in the form of externally threaded elements adjustable in correspondingly threaded bores provided in the frame casing F, each of said supporting elements being provided with a terminal stud portion such as 45 (see Fig. 1) received in the bores of the insulating members 32, 33, 33' 115 and 34, cup-shaped elements 46 being interposed to seat the ends of the said insulating members. With this construction it will be 120

seen that each side of the stator assembly may be adjusted longitudinally or axially with respect to the other side, and both sides may be adjusted relatively to the rotor assembly by micrometrically moving the adjustable elements 41 to 44, and that the stator assembly may be locked in adjusted position by fastening the lock nuts 47, one being provided for each of the adjustable supporting elements.

The rigid casting frame F forms, as will be readily seen, a firm anchoring support for both the rotor and stator assemblies, and this rigid support combined with the minimizing of the strains and stresses in the stator and rotor assemblies due in turn to the adjustability of these parts without introducing unnecessary distortions, results in the production of a condenser construction in which structural changes and resulting instability in service is reduced to a minimum.

For further and more rigidly supporting the stator assembly, I provide means for transversely supporting the stator units in regions intermediate the opposite ends thereof, and preferably such means is designed and constructed to support the stators on the condenser frame to permit the axial or longitudinal adjustment of each of the sides of the stator assembly. More specifically, such means comprises the plurality of angle brackets 48 to 51 each having one leg anchored as by means of a securing screw 52 to the opposite side walls of the frame F and each having another leg bored so that the angle brackets 48 to 51 receive the insulating members 35 to 38 respectively and laterally support the same while permitting axial motion thereof. This manner of supporting the insulating members and the stator assembly not only permits the independent adjustment of opposite sides of the stator assembly, but permits differential expansion and contraction of the parts in longitudinal directions.

For the purpose of matching the condenser units when the same are connected in circuit arrangement, and to match the same so that stray capacities and inequalities in the circuit arrangements and other reactions between parts of the radio receiving set may be compensated for, I prefer to provide compensating condenser units; and in the preferred construction a compensating condenser unit is employed for each of the condenser sets C', C² and C³, such compensating units being generally designated as K', K² and K³. These condenser units are similar in construction and a description of one of the same will, it is thought, suffice for the other two.

It is desired to be able to adjust the compensating condenser unit within a very small range, as between capacities of 5 and 30 micromicrofarads, and it is further desired that the compensating unit should be set in adjustment by simple apparatus and main-

tained in adjusted relation. To accomplish these ends, the compensating unit, such for example as K', comprises a plurality of relatively adjustable elements 54 and 55, the element 54 being electrically connected to the 70 rotor plate set by being attached to the side wall 13 of the frame casing F, said attachment being effected by means of the securing elements 56, and the element 55 being attached to a stator plate set by being secured 75 to a stator post 31 by means of a securing element 57.

Adjustment of the compensating condenser unit is provided by means of an adjusting or set screw 58 threadedly receivable by a 80 correspondingly threaded bore 59 in a stator supporting post 31 (see Fig. 3), the said set screw engaging the end of the adjustable condenser element 54, a suitable insulating washer 60 being interposed between the head 85 of the screw and the condenser element. The condenser element is made in the form of a resilient strip, the resiliency of which is relied upon to hold the strip in any position to which it may be adjusted. Desirably some 90 insulating medium such as a mica piece 61 is interposed between the relatively adjustable elements of the compensating unit. By means of this construction it will now be evident that the simple micrometric adjustment of a screw 58 will effect the movement either in one direction or the other of the compensating condenser element 54, the latter being movable a substantial distance 95 away from its mating element 55 so as to 100 render capable the obtaining of capacity values of extremely low magnitude.

The manner of making the assembly and using the multiple air condenser of my present invention and the manifold advantages 105 thereof will in the main be fully apparent from the above detailed description of the construction and operation of the same. It will be further apparent that while I have shown and described my invention in the 110 preferred form, that many changes and modifications may be made in the structure disclosed without departing from the spirit of the invention, defined in the following 115 claims.

For example, the compensating condensers may be connected to the rotor and stator parts in other ways, and the rotor shaft, in lieu of being metallic, may be made of bakelite so that the rotor plate sets may be insulated one from the other, this producing 120 a construction wherein all of the condenser sets are insulated one from the other.

I claim:

1. A multiple variable condenser comprising a frame, a rotor assembly journalled in said frame and having a plurality of axially spaced rotor plate sets, a stator assembly having a plurality of axially disposed stator plate sets, the rotor plate sets being arranged 130

- to interleave with the stator plate sets to form therewith a plurality of condenser units, means for mounting said stator assembly in said frame along at least two lateral lines of support, said mounting means including insulating members interposed between said stator plate sets and mutually supporting one plate set longitudinally on the other, and means for axially adjusting one side of said stator assembly as a unit relative to the other side thereof.
2. A multiple variable condenser comprising a frame, a rotor assembly journalled in said frame having a plurality of axially spaced rotor plate sets all arranged on the same shaft, a stator assembly mounted in said frame having a plurality of axially disposed stator plate sets arranged so that the rotor plate sets interleave to form therewith a plurality of condenser units, means mounting said stator plate sets insulated one from the other, said mounting means including a plurality of stator supports disposed laterally on opposite sides of said rotor shaft and means for adjusting one of said stator supports relatively to the other to axially adjust one side of said stator assembly as a unit relatively to the other.
3. A multiple variable condenser comprising a frame, a rotor assembly journalled in said frame having a plurality of axially spaced rotor plate sets all arranged on the same shaft, a stator assembly mounted in said frame and having a plurality of axially disposed stator plate sets arranged so that the rotor plate sets interleave to form therewith a plurality of condenser units, means mounting said stator plate sets insulated one from the other, said mounting means including a plurality of stator supports disposed on opposite sides of said rotor shaft, means for adjusting each of said stator supports relatively to the other to axially adjust either or both sides of said stator assembly as a unit, and means supporting the stator assembly at spaced points along said frame permitting the said axial adjustment of the stator assembly.
4. A multiple variable condenser comprising a frame, a rotor assembly journalled in said frame and having a plurality of axially spaced rotor plate sets, a stator assembly having a plurality of axially disposed stator plate sets arranged so that the rotor plate sets interleave to form therewith a plurality of condenser units, means for mounting said stator assembly in said frame along at least two lateral lines of support, said mounting means including insulating members interposed between said stator plate sets and mutually supporting one plate set longitudinally on the other, means for axially adjusting one side of said stator assembly as a unit relative to the other side thereof, and means laterally supporting the stator assembly at spaced points along said frame permitting the axial adjustment of the stator assembly.
5. A multiple variable condenser comprising a frame, a rotor assembly journalled in said frame having a plurality of axially spaced rotor plate sets all arranged on the same shaft, means for axially adjusting on said shaft one rotor plate set relatively to another, a stator assembly mounted in said frame having a plurality of axially disposed stator plate sets arranged so that the rotor plate sets interleave to form therewith a plurality of condenser units, means mounting said stator plate sets insulated one from the other, said mounting means including a plurality of stator supports disposed laterally on opposite sides of said rotor shaft and means for adjusting one of said stator supports relatively to the other to axially adjust one side of said stator assembly as a unit relatively to the other.
6. A multiple variable condenser comprising, in combination, a frame, a plurality of alternately positioned conductive blocks and insulators supported with relation to said frame members along the length thereof, a plurality of sets of stator plates carried by said conductor blocks in spaced relationship, a central rotatable shaft, sets of rotor plates carried by said shaft and arranged to be interleaved between said stator plates for varying the mutual capacity between said sets of plates simultaneously, and means mounted in the end walls of said frame and operative on the opposite ends of said alternately positioned conductive blocks and insulators for adjusting said plurality of sets of stator plates as a unit axially in said frame.
7. A multiple variable condenser comprising a cast metal frame forming an enclosure or housing, a rotor assembly journalled in said frame and having a plurality of axially disposed rotor plate sets, a stator assembly mounted in said frame and having a plurality of axially disposed stator plate sets arranged so that the rotor plate sets interleave to form therewith a plurality of condenser units, the said housing frame comprising end walls, side walls and a bottom wall statically enclosing and shielding the rotor and stator assembly, the depth of said frame casing being at least equal to the diametrical dimensions of said plate sets when arranged out of interleaving relation, mounting and insulation means interposed between the sets of stator plates and between the same and the frame housing for insulating the stator plate sets one from the other and for mounting the same in the housing and means for axially adjusting the mounting means and the stator assembly as a unit in said frame.
8. A multiple variable condenser comprising a metallic frame forming an enclosure or housing, a rotor assembly journalled in said frame and having a plurality of axially dis-

posed rotor plate sets, a stator assembly mounted in said frame and having a plurality of axially disposed stator plate sets arranged so that the rotor plate sets interleave 5 to form therewith a plurality of condenser units, the said housing frame being conductive and comprising continuous side walls statically enclosing and shielding the rotor and stator assembly, the depth of said housing frame being at least equal to the diametrical dimensions of said plate sets when arranged out of interleaving relation, mounting and insulation means interposed between the sets of stator plates and between the same 10 and the frame housing for insulating the stator plate sets one from the other and for mounting the same in the housing, and means for axially adjusting the mounting means and the stator assembly as a unit in said 15 frame.

9. A multiple variable condenser comprising a metallic frame forming an enclosure or housing, a rotor assembly journaled in said frame and having a plurality of axially disposed rotor plate sets, a stator assembly mounted in said frame and having a plurality of axially disposed stator plate sets arranged so that the rotor plate sets interleave to form 20 therewith a plurality of condenser units, the said housing frame being conductive and comprising continuous end walls and side walls statically enclosing and shielding the rotor and stator assembly, the depth of said housing frame being at least equal to the 25 diametrical dimensions of said plate sets when arranged out of interleaving relation, mounting and insulation means interposed between the sets of stator plates and between the same and the frame housing for insulating 30 the stator plate sets one from the other and for mounting the same in the housing, and means for axially adjusting the mounting means and the stator assembly as a unit in 35 said frame.

40 45 Signed at New York in the county of New York and State of New York this 22nd day of January A. D. 1927.

CHARLES HARDY.
